UNITED STATES PATENT OFFICE.

CHARLES O. BURGESS, OF MONMOUTH, ILLINOIS.

FURNITURE.

1,293,025.

Specification of Letters Patent.

Patented Feb. 4, 1919.

Application filed December 22, 1916, Serial No. 138,881. Renewed November 19, 1918. Serial No. 263,236.

To all whom it may concern:

Be it known that I, CHARLES O. BURGESS, a citizen of the United States, residing at Monmouth, in the county of Warren and 5 State of Illinois, have invented certain new and useful Improvements in Furniture, of which the following is a specification.

10 My invention consists in a new and useful improvement in furniture and it is designed to furnish a stand which may be utilized as desired when erected, and folded into minimum of space when not in use. It is adapted particularly to provide a folding stool or table, intended for use by a patient 15 when it is desired to make use of a speculum for any purpose. The embodiment of my invention specifically set forth herein, is designed for use in connection with my improved speculum set forth in application for 20 Letters Patent, bearing Serial Number, 137,754, Dec. 19, 1916, but I desire to claim the use of my invention herein set forth for any and all purposes to which it may be adapted, in connection with various articles 25 of furniture.

The object of my invention is to provide an article of furniture which has stable supports of such character as to furnish a secure foundation for the imposition of great 30 weight when the article is to be used, while said supports are adapted to be folded completely within the compass of the article, when not in use.

In the drawings:

35 Figure 1 is a perspective view of an embodiment of my invention, showing the article in position for use.

Fig. 2 is a bottom plan view showing the parts in folded position.

40 In the drawings:

The numeral 1 designates a stool, embodying my invention, having the U shaped frame 2 having the parallel sides 3 and 4 and the central portion 5, carrying therein a seat 45 6 having its outer edge 6' flush with the upper edge of the frame 2 and its inner edge 6''. The inner edge 6'' is U shaped in form to provide the throat 7 to permit the use of a speculum. Keyed to the outer faces of 50 the sides 3 and 4 are the pivot pins 8, 8, upon

which are pivoted the standards 9, 9, connected by the cross piece 10, forming a continuous strap having the same width as the frame 2. The location of the pins 8, 8, upon the frame 2 and the length of the standards 9, 9, are such that when the standards 9, 9, are swung rearwardly on the pivot pins 8, 8, to lie parallel with the sides 3 and 4 of the frame 2, the cross piece 10 will rest adjacent the central portion 5 of the frame 2, 55 thus folding the continuous strap against the outside of the frame 2, as indicated in Fig. 2. Adjacent the pivot pins 8, 8, are located the stops 11, 11 in such a position as to limit the forward movement of the standards 9, 9, so 60 they will make with the forward portions of the sides 3 and 4, an angle of substantially 45 degrees, thus providing a secure support for the front of the stool 1, as indicated in Fig. 1. Keyed to the inner faces of the sides 65 3 and 4 are the pivot pins 12, 12, upon which are pivoted the standards 13, 13, connected by the cross piece 14, forming a continuous strap having the same width as the frame 2. The location of the pins 12, 12, upon the 70 frame 2 and the length of the standards 13, 13, are such that when the standards 13, 13, are swung forwardly on the pivot pins 12, 12, to lie parallel with the sides 3 and 4 of the frame 2, the cross piece 14 will rest within the lines of the frame 2 thus folding the continuous strap against the inside of the frame 2, as indicated in Fig. 2. Adjacent the pivot pins 12, 12, are located the stops 75 15, 15, in such position as to limit the rearward movement of the standards 13, 13, so they will make with the rear portions of the sides 3 and 4 an angle of substantially 45 degrees, thus providing a secure support for the rear of the stool 1, as indicated in Fig. 1. 80

The forward ends of the sides 3 and 4 are provided with pivot pins 16, 16, upon which are pivoted the parallelly disposed projections 17, 17, having a width slightly less than the sides 3 and 4, which are provided 85 at their forward ends with the symmetrically disposed inward bends 18, 18, beyond which extend the parallelly disposed extensions, 19, 19. The outer end of these extensions 19, 19, are connected by the cross piece 90 95 100

20 provided with the end shoulders 21, 21, which incloses the ends of the extensions 19, 19. Adjacent these shoulders 21, 21, are located, upon the inner faces of the extensions 5 19, 19, the pivot pins 22, 22. Carried upon these pivot pins 22, 22, immediately next to the extensions 19, 19 are the standards 23, 23, which are connected by the cross piece 24, forming a continuous strap of the same 10 width as that of the extensions 19, 19. The location and width of the standards 23, 23, are such that the cross piece 20 serves to limit the forward movement of the standards 23, 23, so that when the standards 23, 23 are extended downwardly from the extensions 19, 15 19, the standards 23, 23, will be allowed to swing forwardly, slightly beyond the perpendicular, thus forming a secure support for the forward end of the extensions 19, 19. 20 Pivoted upon the pivot pins 22, 22, within the standards 23, 23, are the extensions 25, 25 which are provided with the inwardly curved semi-circular bends 26, 26, having their inner ends fastened together by the rivet 27. 25 The extensions 25, 25 are adapted to rest upon and be supported in a horizontal position by the cross piece 20.

The extensions 17, 17, 19, 19, and 25, 25 with the curved portion 26, 26, supply a foot 30 rest for stool 1, which is adapted to be extended in operative position when the stool is to be used by a patient, as indicated in Fig. 1, and which may be folded by turning the extension 25, 25 and the standards 23, 23, 35 upon the pivot pins 22, 22 so that they will lie within and adjacent to the extensions 19, 19. Then by turning the extensions 17, 17 upon the pivot pins 16, 16, the whole folded foot rest is folded to rest under the seat 6 40 within the lines of the frame 2 as indicated in Fig. 2.

Having described my invention, what I claim is:

1. In an article of furniture, the combination of a body portion; and means for supporting same, comprising two continuous straps, pivoted thereto, both adapted to extend at an angle therefrom when opened and one adapted to lie completely therein 45 and the other to lie adjacent thereto, when folded.

2. In an article of furniture, the combination of a body portion, rectangular in form and provided with an outer face and inner 55 face; and means for supporting same, comprising two standards, connected at their lower ends by means adapted to provide a base therefor, which are pivotally connected to the outer face of the body portion and adapted to extend therefrom at an angle 60 when open and lie adjacent thereto when folded, and two standards connected at their lower ends by means adapted to provide a base therefor, which are pivotally connected

to the inner face of the body portion and 65 adapted to extend therefrom at an angle when opened and lie within same when folded.

3. In a stool, the combination of a seat; a frame therefor; a pair of standards connected at their lower ends to form a continuous strap, pivoted to the inner surface of the frame and adapted to extend at an angle therefrom when opened and lie within same 70 when folded; and a pair of standards connected at their lower ends to form a continuous strap, pivoted to the outer surface of the frame and adapted to extend at an angle therefrom when opened and lie adjacent thereto when folded. 75

4. In a stool the combination of a seat; a frame surrounding the seat; two supports pivoted to the inner face of the frame at its rear portion and adapted to be folded within the lines of said frame at its forward portion; and two supports pivoted to the outer face of the frame at its forward portion and adapted to be folded adjacent the outer face 80 of the frame at its rear portion. 85

5. In a stool, the combination of a seat; a frame therefor; a pair of standards connected at their lower ends to form a continuous strap, pivoted to the inner surface of the frame and adapted to extend at an angle therefrom when opened and lie within same 90 when folded; a pair of standards connected at their lower ends to form a continuous strap, pivoted to the outer surface of the frame and adapted to extend at an angle therefrom when opened and lie adjacent thereto when folded; and an extension, pivotally connected to the forward end of said frame, adapted to be extended horizontally therefrom when opened and provided with standards, pivoted thereto, and adapted, when opened, to support it in a horizontal position, and, when folded, to lie completely within the lines of said extension, and further provided with foot rests, pivotally connected thereto, adapted to be extended therefrom horizontally when opened and to lie completely within said extension when folded, said extension being adapted to fold upon its pivotal connection so as to lie completely within the lines of said 100 frame. 105

6. In a stool, the combination of a seat; a frame surrounding the seat; two supports pivoted to the inner face of the frame at its rear portion and adapted to be folded within the lines of said frame at its forward portion; two supports pivoted to the outer face of the frame at its forward portion and adapted to be folded adjacent the outer face of the frame at its rear portion; and an extension, pivotally connected to the forward end of said frame, adapted to be extended horizontally therefrom when opened, and 115 120 125

provided with standards, pivoted thereto, and adapted, when opened, to support it in a horizontal position and, when folded, to lie completely within the lines of said extension, 5 and further provided with foot rests, pivotally connected thereto, adapted to be extended therefrom horizontally when opened and to lie completely within said extension when folded, said extension being adapted to fold upon its pivotal connections so as to lie completely within the lines of said frame. In testimony whereof I affix my signature in the presence of two witnesses.

CHARLES O. BURGESS.
